UNITED STATES PATENT OFFICE.

JOHN J. NOVAK, OF OMAHA, NEBRASKA.

DESIGN FOR AN AUTOMOBILE-TIRE OR SIMILAR ARTICLE.

55,301.

Specification for Design.

Patented May 25, 1920.

Application filed February 3, 1920. Serial No. 355,953. Term of patent 7 years.

To all whom it may concern:

Be it known that I, JOHN J. NOVAK, a citizen of the United States, residing at Omaha, county of Douglas, and State of Nebraska, have invented a new, original, and ornamental Design for Automobile-Tires or Similar Articles, of which the following is a specification, reference being had to

the accompanying drawing, forming part thereof.

The figure is a plan view of a portion of an automobile tire, showing the design.

I claim:

The ornamental design for an automobile tire or similar article, as shown.

JOHN J. NOVAK.
